(57) **CLAIM**

The ornamental design for a sharpener with eraser, as shown and described.

DESCRIPTION

FIG. 1 is an exploded perspective view of a sharpener with eraser, embodying my new design;

FIG. 2 is a front, top, right side perspective view thereof with the cap engaged;

FIG. 3 is a front elevational view of FIG. 2;

FIG. 4 is a front elevational view of FIG. 3 without the cap;

FIG. 5 is right side elevational view of FIG. 3; the left side elevational view being a mirror image thereof;

FIG. 6 is a right side elevational view of FIG. 4; the left side elevational view being a mirror image thereof;

FIG. 7 is a top plan view of FIG. 3;

FIG. 8 is a top plan view of FIG. 4;

FIG. 9 is a bottom plan view of FIG. 3;

FIG. 10 is a bottom view thereof with the sharpener door open;

FIG. 11 is a bottom, front, right side perspective view thereof; and,

FIG. 12 is a bottom, front, right side perspective view of FIG. 10.
